UNITED STATES PATENT OFFICE.

HENRY D. JUSTI, OF PHILADELPHIA, PENNSYLVANIA

ARTIFICIAL TOOTH.

1,241,854.

Specification of Letters Patent.

Patented Oct. 2, 1917.

Application filed October 19, 1916. Serial No. 126,493.

To all whom it may concern:

Be it known that I, HENRY D. JUSTI, a citizen of the United States, residing in the city and county of Philadelphia, State of Pennsylvania, have invented a new and useful Artificial Tooth, of which the following is a specification.

My invention consists of an artificial tooth which is provided therein with an angular 10 opening therethrough forming a vent which is open at the exterior of the tooth to allow the escape of air therefrom, so that there will be a free flow of the plastic material or metal thereinto, forming a perfect anchorage for said material or metal in the tooth and preserving in the main the strength of 15 the tooth.

The invention is satisfactorily illustrated in the accompanying drawing, but the important instrumentalities thereof may be varied, and so it is to be understood that the invention is not limited to the specific details shown and described.

Figure 1 represents a perspective view of 25 an artificial tooth embodying my invention.

Fig. 2 represents a longitudinal section thereof on line 2—2 Fig. 1.

Fig. 3 represents a top plan view thereof.

Fig. 4 represents a vertical section of a 30 modification.

Similar numerals of reference indicate corresponding parts in the figures.

Referring to the drawings.

1 designates an artificial tooth, which excepting the feature of my invention applied thereto, is of usual construction.

In the body of the tooth is an opening or passage which is of angular form, one limb 2 of which extends therein in the longitudinal axis of the tooth, and the other limb 3 thereof extending therein in the transverse axis of the tooth and communicates with said limb 2, both limbs opening outward respectively in diametrically different places 45 on the exterior of the tooth, say at the lap-ridge end and the lingual side of the tooth, said opening forming an unobstructed vent for air to escape therethrough in the subse-

quent admission of the plastic material or metal therein, avoiding the possibility of an air cushion in said opening, and so causing a perfect anchorage of said material or metal in the tooth, and a consequent strong attachment of the tooth and material and metal one with the other. It is to be noted that the bottom of the limb 3 and the bottom of the limb 2 are coincident, there being no opening below the bottoms of said limbs. It will also be noted that the walls of the limb 3 are not undercut but extend substantially parallel.

Furthermore, the outer terminal of the limb 3 of the opening is intermediate of the rear portion 4 of the neck of the tooth and the biting edge thereof, thus leaving said portion intact and solid, and so it is not liable to spread, whereby its strength is preserved. The attachment of the plate material with the tooth is still further increased by the cavity 5 in the tooth at the lap ridge, the latter forming the surrounding wall of 70 said cavity whereby said material will enter the latter as well as said angular passage and so be anchored in both passage and cavity.

In Fig. 4, the rear portion 4 of the neck is slightly different in that it is of less thickness than that of the other figures, and the limb 3 of the opening is reduced in length without, however, producing different results from those hereinbefore stated.

Having thus described my invention what I claim as new and desire to secure by Letters Patent, is:—

An artificial tooth having a passage of an angular form extending therethrough and a cavity in the lap ridge thereof, one end of said passage terminating at the lingual side of the tooth and the other end terminating at said cavity and in communication therewith.

HENRY D. JUSTI.
